TOY SEWING MACHINE

Shigeaki Kuramochi, 44 1-chome Kohinada-Daimachi,
Bunko-ku, Tokyo, Japan

Filed Oct. 11, 1965, Ser. No. 87,386

Term of patent 14 years

(Cl. D34—15)

FIG 1

FIG 2

FIG 3

FIG 4

FIG. 5

FIG. 6

FIG. 1 is a front elevation view of the toy sewing machine showing the new design;

FIG. 2 is a left-hand end elevation view thereof;

FIG. 3 is a top plan view thereof;

FIG. 4 is a rear elevation view thereof;

FIG. 5 is a right-hand end elevation view thereof; and

FIG. 6 is a bottom plan view thereof.

The dominant features of my design reside in the full line portions shown.

I claim:

The ornamental design for a toy sewing machine, as shown and described.
